GAME APPARATUS

Leonardo Colaluca, Somerville, N. J.

Application August 2, 1939, Serial No. 288,049

1 Claim. (Cl. 273—47)

The invention relates to a game apparatus and more especially to an apparatus for playing ten pins.

The primary object of the invention is the provision of an apparatus of this character wherein a stand supports a game table imitative of a bowling alley wherein ten pins can be played either by a cue or by rolling balls in the direction of set up pins and such balls when played will be returned to a player, the apparatus being of novel construction and lends amusement and entertainment to players of the game.

Another object of the invention is the provision of an apparatus of this character wherein the structure thereof enables the playing of a game of ten pins either indoors or outdoors without the necessity of a permanently built standard size of bowling alley in that the apparatus is of miniature size and is readily portable from one location to another.

A further object of the invention is the provision of an apparatus of this character wherein the ten pins and balls used therewith are readily recoverable and the balls can be returned to a player after the playing thereof in that said balls when delivered to a chute through gravity will be brought to a returned position.

A still further object of the invention is the provision of an apparatus of this character which is simple in its construction, thoroughly reliable and efficient in operation, its construction eliminates the necessity of players stooping when sending the ball for the striking of the pins in the playing of the game of ten pins, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a mutilated top plan view of the apparatus constructed in accordance with the invention, showing associated therewith a cue device constituting the subject matter of another application for patent and a ball sent therefrom.

Figure 2 is a view similar to Figure 1 with the cue device removed.

Figure 3 is a sectional view taken on the line 3—3 of Figure 2 looking in the direction of the arrows.

Similar reference characters indicate corresponding parts throughout the several views in the drawing.

Referring to the drawing in detail, the apparatus constructed in accordance with the invention is generally denoted at A while B is a cue device for use with the apparatus and this device is the subject matter of a separate application for patent filed August 2, 1939, and serially numbered 288,048.

The apparatus A comprises a legged stand, a portion thereof being indicated at 10 for supporting a substantially rectangular shaped table involving a bed 11, side walls 12 and opposite end walls 13 and 14, respectively, these walls being perpendicular and extend for a major portion of the length of the bed slightly elevated from the plane thereof while the minor portion of the side walls 12 together with the end wall 14 are elevated a considerable distance above the plane of the bed 11 to effect a trapping space 15. Superimposed upon the bed 11 and extending a distance from the end wall 13 into the trapping space 15 but removed from the wall 14 thereof is a flat level ball runway 16, being of uniform width considerably less than the width of the table A for a major portion of the length of said runway and the minor portion constitutes a flared or fan spread like pin setting terminal 17 which is also spaced from the side walls 12 and the end wall 14. This terminal 17 constitutes a pin setting area for ten pins 18 while a ball or balls 19 are adapted to travel the runway for the striking and upsetting of the ten pins 18 when set up for the purpose of playing a game of ten pins in the use of the apparatus.

The end wall 13 is medially cut away at 20 so as to enable the convenient sending of the ball 19 in the runway 16 for the striking of the ten pins 18 at the terminal 17, the setting arrangement being shown in Figures 1, 2 and 3 of the drawing.

The table A is fastened upon the legged stand 10 so that said table will be level in the supporting thereof by the stand. Within the trapping space 15 is arranged an inclined board 21 which extends from the bed 11 contiguous to the wall 14, the latter being equipped with a cushioning device or pad 22 at the striking side thereof when the pins 18 have been knocked down and tumble topsy-turvy into the trapping space 15, the board 21 being for the purpose of directing the sent balls 19 through an exit 23 from the space 15 communicative with a return chute 24 being inclined in the direction of the wall 13 so

that the balls gravitating in this chute 24 will return to the player of a game in the use of the apparatus. The chute at the end thereof next to the wall 13 is readily accessible to retrieve balls 5 therefrom. The chute 24 is maintained fixed in the stand at the forward inclination stated.

The exit 23 has projected thereinto an inherently resilient guard 25 so that balls being passed through the said exit 23 will be checked against 10 return to the trapping space 15 but will be assured of gravitating for a return to a player in the chute 24.

The table A at opposite longer sides of the ball runway 16 is provided with depressed alleys 15 or gutters 26 so that if the balls 19 in the sending thereof swerve from a straight course, will roll into the alleys or gutters 26 and be directed into the trapping space 15 without effecting a strike of the set pins 18 for the upsetting thereof.

20 The cue device B is adapted for swivel mounting on the table A and the latter has provided therein the pivot pin opening 27 of the swivel pin, not shown, of the said device B, which latter is described in detail in the said application filed August 2, 1939, serially numbered 288,048.

25 The balls can be sent over the runway 16 either by hand rolling thereof or by the use of the device B or an ordinary billiard or pool cue, not shown. The playing of the game of ten pins in miniature 30 style by the use of the apparatus is most interesting and for the winning of the game requires skill on the part of the player resultant in entertainment and amusement to such players, being either an outdoor or indoor game.

35 The game apparatus hereinbefore described is adaptable for use as a miniature shuffle board and in this instance in substitute for the balls discs or the like will be employed as playing pieces. Additionally the game apparatus can be 40 used for the playing of games involving movable play pieces.

The terminal 17 of the ball runway 16 having the flared or spread formation disposes the ten pins 18 at the sides of the group thereof when

in set position laterally of the said runway 16 thus making it difficult for the striking of these pins by the balls when thrown due to the fact that each ball having striking of said pins will travel off of the runway into the gutters at opposite sides of the latter by reason of the fact that such pins are not disposed in a direct line with the said runway. This construction just mentioned creates a tendency for the ball to roll off of the runway before striking the laterally 10 offset pins of the group at the terminal 17.

What is claimed is:

A game apparatus comprising a substantially rectangular shaped table having a bed, side walls and opposite end walls, respectively, the side and end walls being vertical to the bed and extending for a major portion of the length thereof with the minor portion of the said side walls together with one end wall elevated a considerable distance above the plane of said bed for effecting 20 a trapping space, a flat level ball runway superimposed upon said bed and carried into the trapping space and having a uniform width considerably less than the width of the table for a major distance thereof and a minor flared fan 25 spreadlike portion constituting a pin-setting terminal within the said trapping space, vertical side and end walling immediately beneath the terminal, a chute opening into the trapping space beyond opposite sides and the end adjacent thereto of the said setting terminal and being inclined away from the said trapping space with the lowermost end of the said chute terminating remote from the said space, and an inclined board within the trapping space with the incline of such board 30 reversed to the incline of the chute for gravity action of the pins from the terminal when knocked therefrom and their delivery into the trapping space, the end walling beneath the terminal and the inclined board having registering 40 openings for the passage of a ball only therethrough to the chute.

LEONARDO COLALUCA.
